LEE PAYTON, OF PINE GROVE, CALIFORNIA, AND ONE-FOURTH TO JOSEPH W.
PRESTON, JR., OF SAN FRANCISCO, CALIFORNIA.

ORE-MILLING MACHINE.

1,391,301.

Specification of Letters Patent. Patented Sept. 20, 1921.

Application filed November 26, 1919. Serial No. 340,703.

To all whom it may concern:

Be it known that I, JOHN J. CRANMER, a citizen of the United States, residing at Pine Grove, in the county of Amador and State 5 of California, have invented new and useful Improvements in Ore-Milling Machines, of which the following is a specification.

This invention relates to an ore milling machine and particularly to a machine in 10 which a grinding and stamping action is obtained. One of the objects of the present invention is to provide a simple substantial ore milling machine in which both a grinding and stamping action is employed for the 15 reduction of ore; also a mill which will reduce the ore in the best possible condition for treatment by a concentration, cyaniding or amalgamation and which is designed to amalgamate the coarse as well as the fine 20 gold inside the mill and without flouring.

Another object of the invention is to provide an impact action and wash of the water employed which will insure immediate discharge of the ore on reaching the necessary 25 degree of fineness and return the oversize under the mullers thereby preventing sliming and unnecessary regrinding of the ore.

Another object of the invention is to provide a mill which is so constructed that all 30 parts subject to wear, such as the grinding dies, shoes, etc. may be readily removed and replaced when worn.

Further objects will hereinafter appear. 35 The invention consists of the parts and the construction, combination and arrangement of parts as will be hereinafter more fully described and claimed, having reference to the accompanying drawings, in 40 which—

Figure 1 is a central, vertical, section of the mill.

Fig. 2 is a plan view of the rotor and the mullers propelled thereby.

Fig. 3 is a side elevation, partly in section, 45 of one of the mullers.

Referring to the drawings in detail and particularly Fig. 1, A indicates a base frame in which is centrally positioned and journaled a vertically disposed driving shaft 2 to which power is transmitted in any suitable manner or as here shown by means of gears 3. Secured on the upper end of the shaft is a rotor 4 and pivotally mounted in

the rotor as at 5 are a plurality of radially disposed arms 6. Journaled on the free end of each arm is a muller 7 and forming a trackway and support for the mullers is an annular bottom die 8 which is secured in an annular channel 9 formed in the base frame. 60 The die 8 may be secured in any suitable manner and it may be built in sections if desired to permit ready removal or replacement of the same when worn. Formed on each side of the annular die 8 is an annular 65 groove 10, the function of which will hereinafter be described. Formed on the outer edge of the base frame is an annular screen frame 11 and suitably secured in said frame are a series of screens 12. 70

The ore to be ground or reduced is in this instance delivered to a central hopper 12' supported by the rotor 4, and it is in turn distributed to the mullers 7 by means of radially disposed downwardly extending 75 pipes 13 which terminate in front of the mullers. The ore is in this manner delivered to the mullers as fast as they can reduce the same and the ore is discharged through the screens 12 on reaching the necessary 80 degree of fineness.

The most important feature of the present invention is the construction of the mullers. By referring to Figs. 2 and 3, it will be seen that each muller is provided with a series of 85 cam shaped shoes 14, said shoes being so positioned that they slightly overlap each other as at 15 and each shoe being provided with an inwardly extending lug 16 through which is passed a securing bolt or pin 17. The 90 shoes taper from end to end, all being heaviest at the lug end and the thinnest at the forward end. The faces of the shoes are curved or annular as shown, and I therefore form a series of off-set cam faces which produces a combined grinding and stamping action during the rotation of the mullers. The shoes are in this instance shown as removable to permit renewal of the same when worn, but I wish it understood that the off-set cam faces produced by the shoes may be formed directly in the face of the muller if desired. In actual operation with power transmitted to shaft 2, it can readily be seen that a rotary motion will be transmitted to the rotor 4 and the arms 6 carried thereby; similarly, that the mullers will rotate about the free ends of the respective arms and will 95 100 105

simultaneously travel around and around on the annular bottom die 8. Ore delivered by means of the hopper 12' and the pipes 13 will thus be deposited in front of the respective mullers and will thereby be crushed due to the grinding and stamping action produced; that is, the off-set cam faces formed by the shoes 14 will permit each muller to drop when grinding over the heavy end of each shoe, thereby producing a stamping action, and the grinding action will take place while the muller is traveling over the curved faces of the shoes. The stamping action produced is of further importance, as it not only materially increases the output of the mill, but it also produces an ideal wash action which insures immediate removal of the reduced ore through the screens when the ore has reached the necessary degree of fineness; that is, the drop of the mullers when riding over the off-set cam sheets produces a splash or wave action which removes the fines and returns the oversized to the mullers. Another important feature of the present invention is the provision of the annular grooves 10. These serve the function of amalgam traps and thereby prevent the escape of quick or amalgam which might otherwise flour and pass through the screens. Perfect amalgamation both of coarse and fine gold can therefore take place directly within the mill and an ample quantity of quicksilver may be employed as the danger of loss by flouring is practically prevented. Sliming of the ore 35 is also reduced to a minimum as the wash action produced by the drop and rotary movement of the mullers immediately removes the fines the moment they have been reduced to such a size that they may escape through the screens. A large screen surface is also provided thereby insuring increased capacity and general efficiency.

While a more or less specific design of mill is here shown, I wish it understood that the 45 invention may be applied to practically any standard form of mill. I therefore wish it understood that changes in design and proportion may be resorted to; similarly, that the materials and finish of the several parts 50 employed can be such as the experience and judgment of the manufacturer may dictate and varying conditions may demand.

Having thus described my invention, what I desire to secure by Letters Patent is:—

1. In an ore milling machine, a muller, a 55 plurality of shoes secured on the outer face of the muller, said shoes being cam-shaped and presenting a high and a low end, means permitting overlapping of the shoes to permit the formation of a continuous covering 60 on the muller, a plurality of recesses formed in the face of the muller, and a securing lug on each shoe adapted to be received thereby.

2. In an ore milling machine, a muller, a 65 plurality of shoes secured on the outer face of the muller, said shoes being cam-shaped and presenting a high and a low end, a recess formed in the high end of each shoe for the reception of the rear low end of the shoe disposed in front thereof, and a single securing 70 means for each shoe.

3. In an ore milling machine, a muller, a 75 plurality of shoes secured on the outer face of the muller, said shoes being cam-shaped and presenting a high and a low end, a recess formed in the high end of each shoe for the reception of the rear low end of the shoe disposed in front thereof, a plurality of recesses formed in the outer surface of the muller, a lug on each shoe adapted to be received by 80 said recesses, and means for securing the lugs and shoes against removal with relation to the recesses.

4. In an ore milling machine, a muller, a 85 plurality of curved cam-shaped shoes on the outer face of the muller, the forward high end of each shoe partially overlapping the rear low end of the shoe disposed in front thereof to secure the rear end of each shoe and to form a continuous covering for the 90 muller, a lug formed on the inner end of each shoe adjacent the forward overlapping end, a plurality of recesses in the outer face of the muller for the reception of the respective lugs, and means carried by the muller extending through the recesses and the lugs to 95 secure the same against removal.

In testimony whereof I have hereunto set my hand in the presence of two subscribing witnesses.

JOHN J. CRANMER.

Witnesses:
